FRAME HANDBAG

Max Grossman, Jersey City, N. J.

Application June 19, 1952, Serial No. 20,273

Term of patent 7 years

(Cl. D87—3)

To all whom it may concern:

Be it known that I, Max Grossman, a citizen of the United States, residing at Jersey City, in the county of Hudson and State of New Jersey, have invented a new, original, and ornamental Design for a Frame Handbag, of which the following is a specification, reference being had to the accompanying drawing, forming part thereof.

In the drawing:

Fig. 1 is a front perspective view of a frame handbag, with its cover opened, showing my new design;

Fig. 2 is a rear perspective view of the handbag with the cover closed; and

Fig. 3 is a bottom view of the same.

I claim:

The ornamental design for a frame handbag, as shown.

MAX GROSSMAN.
